FLEXIBLE CARD MOUNTING

Edwin H. Smythe, Evanston, Ill.

Application July 18, 1932, Serial No. 623,161

18 Claims. (Cl. 129—16)

My invention relates to cards for use as indexes or information cards and has for its principal purpose the provision of a hinged card in combination with means whereby a portion of the card is yieldingly urged into a certain definite position with respect to another portion of the card which may be held in a suitable container of any type.

In the copending application of myself and Frederick H. Loveridge, Serial No. 623,160, filed July 18, 1932, for Card indexes and the like, we have disclosed a card container in which the cards are so mounted that they are normally held in superposed relation although they may be pulled forward and allowed to flip back one at a time into normal position.

My invention concerns itself more particularly with providing a card having a portion serving as a base portion and another record receiving or display portion hinged thereto with means for resiliently urging this record portion in one direction relatively to the base portion, so that a group of the cards may be mounted in a suitable container so that the cards are normally yieldingly held together in superposed relation, but may be swung apart to reveal the proximate surfaces of adjacent cards and released one or more at a time to return to normal position.

I will describe the preferred form of my invention by reference to the accompanying drawings wherein—

Fig. 1 is a longitudinal section through a card holding device utilizing a plurality of cards embodying my invention;

Fig. 2 is a plan view of one of the cards employed in Fig. 1;

Fig. 3 is a view illustrating a slightly modified form of card; and

Fig. 4 illustrates a further modification.

Referring now in detail to the drawings, the container 5 shown in Fig. 1 is merely an illustration of one manner of mounting the cards. This container has the upwardly extending back wall 6 and is provided with a trough extending forwardly from this back wall to receive the cards 7, adequate spacers 8, a filler block 9, and a suitable clamping block 10 which is caused to clamp the cards in place by means of the screw 11. These cards are so formed that they may be bent along the line indicated at 12 so they may be turned forward through all positions to the full lower position indicated at 13 in Fig. 1. The ordinary card is incapable of withstanding this kind of bending and returning to its original position so I have provided means whereby sufficient force

can be applied to the top portion 14 of the card to carry it back into the full line position shown in Fig. 1.

I preferably crease the card as indicated at 15 between the top portion 14 and the lower portion 16 and cut it out as by means of the punched holes 17 to form flexible connecting tongues. I then place the spring wire 18, bent as shown in Fig. 2, on the card by inserting the central upstanding brace portion 19 from the back, and then inserting the end portions 20 into the position shown in Fig. 2. Now when the top of the card is bent forwardly the result is to twist the spring between the portions 20 and the portion 19, and, when the card is released, this spring will return the card to the original position. The torsion in the spring being spread over the entire length between the members 20 and the member 19 is not sufficient to permanently distort the spring, thus ensuring the card's return to its original position.

Now when the cards equipped in this fashion are placed in a container such as 5 with suitable spacers such as 8 between them, it is evident that when the cards are pulled down horizontally over the front part of the container, their front or top edges will be spaced apart a distance depending upon the thickness of the spacers 8. This makes it easy for one who is looking through the card list to slide his fingers forwardly over the edges of the cards and let them return one at a time to the upright position. Thus one can quickly run through the entire card list and find any information thereon he desires.

In Fig. 3, a similar card to that shown in Fig. 2 is illustrated, but in this card, the top portion 21 and the bottom portion 22 are connected by a flexible member 23 such as a piece of linen cloth which is pasted to the backs thereof, and a spring 24 is pasted between the card portions 21 and 22 and the member 23. This spring is bent as indicated at 25, 26, and 27 so that when the top of the card is pulled forward it causes a twisting of the portions 28 and 29 of the spring wire which will return the card to its original position when the card is released.

In the form shown in Fig. 4, a top portion 30 and bottom portion 31 of the card are secured again by means of a linen strip 32 pasted on the backs thereof and a spring 33 having the downturned end at 34, and the upturned end at 35 extends diagonally across the member 32 and lies between this member 32 and the portions 30 and 31 of the card. It is evident that in this case as before bending of the card forward twists the spring

wire so that the energy stored up in the spring will return the card to its original position. Either one of these three forms of cards may be used in a base such as that shown in Fig. 1.

5. From the above description, it is believed that the construction and operation of this device will be clear to those skilled in this art.

Having thus described my invention, what I claim as new and desire to secure by Letters Patent is:

10. 1. A device of the character described comprising a plurality of card-like elements adapted to receive legends or the like, a support for said elements, said elements having mounting means at corresponding edges thereof forming parts thereof and resilient means individual to said elements tending to yieldingly swing them in one direction relative to said mounting means whereby, when said elements are swung in the opposite direction and successively released, said resilient means successively restore them to their original position to thus successively display said legends.

20. 2. A device of the character described comprising a plurality of card-like elements adapted to receive legends or the like, a support for said elements, said elements being spaced apart along one edge, said elements having mounting means at corresponding edges thereof forming parts thereof, and resilient means individual to said elements tending to yieldingly swing them in one direction relative to said mounting means whereby, when said elements are swung in opposite direction and successively released, said resilient means successively restore them to their original position to thus successively display said legends.

30. 3. A card element for receiving and displaying legends or the like having a display portion and a mounting portion hingedly connected to each other together with means tending to yieldingly swing the display portion in one direction relatively to the mounting portion.

40. 4. A card element for receiving and displaying legends or the like having a display portion and a mounting portion hingedly connected together with means tending to yieldingly swing the display portion in one direction relatively to the mounting portion, said means comprising a spring member having portions mounted on each of the aforesaid portions.

50. 5. A card element for receiving and displaying legends or the like having a display portion and a mounting portion hingedly connected together with means tending to yieldingly swing the display portion in one direction relatively to the mounting portion, said means comprising a spring mounted on said portions.

60. 6. A card element for receiving and displaying legends or the like having a display portion and a mounting portion hingedly connected together with means tending to yieldingly swing the display portion in one direction relatively to the mounting portion, said means comprising a spring mounted between said portions and having extensions engaging said portions at spaced points along their meeting edges.

70. 7. A card element for receiving and displaying legends or the like having a display portion and a mounting portion hingedly connected together with means tending to yieldingly swing the display portion in one direction relatively to the mounting portion, said means comprising a spring mounted between said portions and having extensions engaging said portions at spaced points along their meeting edges, the spring between said points being free whereby

the distortion caused by swinging the display portion is spread over a considerable length of spring.

8. A card having a display portion and a base portion and a transversely creased intermediate portion to constitute a hinge therebetween, and spring means carried by said card and tending to swing said display and base portions about said hinge, back into their normal relative positions when displaced therefrom.

9. A card having a display portion and a base portion and a transversely creased intermediate portion to constitute a hinge therebetween, and a torsion spring lying along said crease and tending to swing said display and base portions about 15 said hinge, back into their normal relative positions when displaced therefrom.

10. A card having a display portion and a base portion and flexible connecting tongues therebetween formed by a transverse line of perforations to constitute a hinge, and spring means carried by said card and tending to swing said display and base portions about said hinge, back into their normal relative positions when displaced therefrom.

20. 11. A card having a display portion and a base portion and a transversely creased and perforated intermediate portion to constitute a hinge therebetween, and a torsion spring carried by said card and tending to swing said display and base 25 portions about said hinge, back into their normal relative positions when displaced therefrom.

30. 12. A device of the character described comprising a plurality of card-like elements adapted to receive and display legends or the like and each having a display portion and a mounting portion hingedly connected to each other, a support for said elements having provision for releasably clamping the mounting portions of said elements in fixed position on the support together with resilient means individual to the card elements tending to yieldingly swing the display portions in one direction relatively to their respective mounting portions.

35. 13. A card display device, including a plurality of cards each having a display portion and a base portion flexibly hinged together, separator elements interposed between the base portions of adjacent cards, and springs each of which is arranged and adapted to exercise a 40 turning force as between a separator element and the display portion of an associated card.

45. 14. A card display device, including a plurality of cards each having a display portion and a base portion flexibly hinged together, separator elements interposed between the base portions of adjacent cards, and a spring for each card having one end held against movement and the other end adapted to exercise a turning force upon the display portion of the associated card.

50. 15. A card display device, including a plurality of cards each having a display portion and a base portion flexibly connected together, means for securing the base portions of said cards together, and a plurality of springs having one end of each held immovable by said securing means and the other end adapted and arranged to exercise a turning force upon the display portion of a particular one of said cards.

60. 16. A card display device, including a plurality of cards each having a display portion and a base portion flexibly hinged together, means for securing the base portions of said cards together in fixed relation, and a plurality of torsion springs, one end of each of which is held against 70

turning by said securing means and the other end of each of which has operative relation with the display portion of a particular one of said cards.

5 17. A card display device, including a plurality of cards each having a display portion and a base portion flexibly hinged together, means for holding the base portions of said cards in fixed relation with each other, and a plurality of torsion springs each arranged to lie along the hinge between the display portion and base of a particular card, each of said torsion springs having a part held against turning by said holding means and another part in operative rela-

tion with the display portion of a particular card.

18. A card element for receiving and displaying legends or the like having a display portion and a mounting portion hingedly connected to each other together with means permanently affixed to said element tending to yieldingly hold said display portion in one definite position with respect to the mounting portion, said means operating to return the display portion to said position when it is moved in one direction away from said position.
